UNITED STATES PATENT OFFICE

SYDNEY S. CHADDERTON, OF SAN FRANCISCO, CALIFORNIA, ASSIGNOR TO STANDARD OIL COMPANY OF CALIFORNIA, OF SAN FRANCISCO, CALIFORNIA, A CORPORATION OF DELAWARE

DESIGN FOR AN AIRPLANE

Application filed June 21, 1930. Serial No. 36,118. Term of patent 14 years.

To all whom it may concern:

Be it known that I, SYDNEY S. CHADDERTON, a citizen of the United States, residing in the city and county of San Francisco, State of California, have invented a new, original, and ornamental Design for an Airplane, of which the following is a specification, reference being had to the accompanying drawing, forming part thereof.

In the drawings:

Fig. 1 is a front elevation;
Fig. 2 is a side elevation, and
Fig. 3 is a top plan view of an airplane showing my new design.

The surface ornamentation constitutes the dominant feature of the design.

I claim:

The ornamental design for an airplane, as shown.

SYDNEY S. CHADDERTON.
